UNITED STATES PATENT OFFICE.

JOHN O. KLEIN, OF ALLIANCE, OHIO.

TIE AND RAIL FASTENER.

1,396,581.

Specification of Letters Patent.

Patented Nov. 8, 1921.

Application filed December 31, 1920. Serial No. 434,209.

To all whom it may concern:

Be it known that I, JOHN O. KLEIN, a citizen of the United States, residing at Alliance, in the county of Stark and State of Ohio, have invented a certain new and useful Improvement in Tie and Rail Fasteners, of which the following is a full, clear, and exact description, reference being had to the accompanying drawings.

10 My device relates to a tie and rail fastener designed particularly to prevent creeping of the rail by utilizing the force tending to cause creeping to more firmly bind the rail to the tie. Another object is to provide a 15 fastening of such character that it may be very readily installed and removed, but will be effective when in use. A further object is to provide a fastening adapted to coöperate with a cast metal tie which shall be 20 strong enough to firmly hold the rails in position, but shall be of light and comparatively cheap construction. Further objects of the invention and features of novelty will be apparent in the course of the following 25 description and claims.

Referring to the drawings in which a preferred embodiment of my invention is shown, Figure 1 is a top plan of a tie embodying my invention and showing the rails attached thereto. Fig. 2 is a side view of the same. Fig. 3 is a bottom plan of the tie. Fig. 4 is a fragmentary approximately isometric perspective view of one end of the rail tie. Fig. 5 is a section on line 5—5, 35 Fig. 2.

Referring to the different parts by numeral, 10 is a rail tie having the spaces 16 and 17, 18 formed therein so as to prevent waste of material and at the same time having its rail receiving portion of full thickness so as to have sufficient strength to form a firm seat for the rails. This tie may advantageously be a cast steel structure.

The tie 10 may be provided on its upper 45 surface with the rail flange engaging members 12. These members may be all integral with or suitably adapted to the tie 10, and the inner vertical ends adjacent the rail extend perpendicular to the sides of the tie in 50 the usual manner. Opposite each set of these engaging members a parallel-sided channel 14 is provided. This channel may be H-

shaped in cross section as shown, so as to form a firm seat for the flange-carrying member subsequently described.

55

This channel has its sides extending transversely to the sides of the tie, but not perpendicular thereto. Each of these channels has its sides therefore closer to the line formed by the rail flange engaging portions 60 of the coöperating lugs 12 on one side of the tie than on the other side, and the channels are closest to the line mentioned on the same side of the tie in each case. The exact angle, which the channel makes with the sides of 65 the tie is, of course, not important, though I have found that the acute angle of about 83° gives a very satisfactory result.

Adapted to seat in the channels, which have been described, are parallel-sided members 20, which are complementarily formed so as to engage these channels respectively, and carry on their upper surfaces rail engaging flanges 21, which are adapted to engage that flange of each rail 30, respectively, 75 which is not engaged by the lugs 12.

In Fig. 1 I have shown the sliding members in slightly different position with relation to the tie, the showing at the right representing the position which the member 80 would take when new and the position of the member on the left being the position that it would take, if it were somewhat worn.

In order to provide means for reinforcing the rail laterally, as for instance, when the 85 rail is on a curve, I have shown the lug 15 which may be formed between lugs 12 and integral with, or suitably attached to the tie 10.

It will be seen that by having each channel converge toward its coöperating lugs 12 at the same side of the tie causes the thrust due to the passage of a train over the tie to have the same effect at each end, that is, the train will tend to thrust the lugs 21 toward 95 their coöperating lugs 12 to more firmly grip the rail and prevent its creeping, or if the train is going in the other direction the force would tend to drive the lugs 21 away from their coöperating lugs 12.

100 Where the device is to be used on a double track system, therefore, the tie should be so placed that the channels will converge from the lugs 12 in the direction in which the rails

tend to creep. That is, if the force tending to cause creep acts to move the rail in the direction shown by the arrow in Figs. 1 and 5, the channels would be arranged as shown in these figures. In any case where the tendency to creep might be found to be sometimes in one direction and sometimes in the other, the ties might be arranged so as to have the channels on alternate ties converge 10 in opposite directions.

When it is desired to use the invention in connection with a single track system, the successive ties might advantageously be placed with their channels converging in opposite directions so that any single train 15 passing over the track will tend to more firmly clamp the rail to each alternate tie, and the rail would be so firmly held that there could be no appreciable creeping 20 thereof. A train passing in the other direction would tend to clamp the rails on the other set of alternate ties.

The anti-creeping feature of the invention is especially needed, however, where a 25 double track system is employed, because with a single track system, the traffic being about the same in one direction as the other, will itself tend to counteract the creeping tendency.

30 In the double track system, however, where the trains continually move in one direction only over the track, there is a continuous and considerable creep of the rails unless some means is provided to prevent it.

35 It will be seen that I have provided a simple and efficient method of preventing such creep, by means of a device which may be easily and cheaply manufactured. It will further be seen that the flange carrying 40 movable members are operable and self-adjusting until their flanges are completely worn away when used on a double track system, for the creep of the rails caused by the passing of the train thereover will move them up as they wear away to maintain 45 them in tight clamping relationship without necessitating any adjustment by the employees of the road.

While I have described a specific embodiment of my invention, it will be apparent 50 that modifications embodying the principles thereof may be made, and therefore, the foregoing description is to be taken as illustrative and not restrictive.

55 I claim:

1. In a device of the class described, a rail tie having an obliquely extending channel in its upper face and a rail engaging member occupying such channel, said member having 60 a face extending under the rail and adapted to form a seat for the lower surface thereof.

2. In a device of the class described, a rail tie having a transverse channel in its upper face with a wide portion at its top 65 and an undercut portion in said channel,

said channel extending obliquely in plan view, and the upper portion thereof extending in position to be covered by a rail.

3. In a device of the class described, a rail tie having transversely extending channels H-shaped in cross-section therein, said channels extending obliquely to the sides of the tie, one side of said H channel opening 70 through the upper face of the tie.

4. In a device of the class described, a rail tie, an oblique wide channel in said tie opening through the top face of the tie and a flange-engaging lug outward of the channel and adjacent thereto, the upper portion of the channel extending closer to the lug than the width of the lower flange of a rail. 75

5. In a device of the class described, a rail tie having a transverse channel in its upper face and an undercut portion in said channel, means on the tie for engaging a rail flange said channel being oblique to the sides of the tie and a member slidible in said channel and having a rail engaging lug thereon, and a face for engaging the lower 80 face of said rail, and extending under the central portion thereof. 85

6. In a device of the class described, a rail tie having transversely extended H-shaped channels therein, said channels being oblique to the sides of the tie and a complementarily formed member in said channel and having rail engaging means thereon. 90

7. In a device of the class described, a rail tie, a channel oblique to the side of the tie adjacent each end of said tie, a flange engaging lug adapted to engage a rail flange adjacent thereto and a member in said channel having a lug adapted to engage the other rail flange, and a face engaging the lower 105 face of the rail. 100

8. In a device of the class described, a rail tie, obliquely extending channels adjacent the ends thereof, rails on said tie, a member in each channel having a lug engaging a flange of the adjacent rail and a face supporting the lower face of the rail, and fixed lugs engaging the opposite flange of each rail respectively. 110

9. In a device of the class described, a rail tie having transverse oblique channels adjacent each end thereof, rail engaging lugs on said tie adjacent said channels, said channels extending closer to the lugs than the width of a rail and members having flange 115 engaging lugs thereon, and a portion mounted in said channels, and adapted to engage the bottom face of the rails respectively. 120

10. In a device of the class described, a rail tie having transversely extending H-shaped channels therein, said channels being oblique to the sides of the tie, and one of the H-shaped sides extending through the upper face of the tie, complementarily formed members in said channels having rail en- 125 130

gaging means thereon, comprising a lug for engagement with the inner side of the rail flanges respectively, said members each having a face in contact with the under side of 5 a rail and means carried by the tie and outward of said channels respectively for engaging the outer flanges of the rails.

11. In a device of the class described, a rail tie, rails thereon, a set of fixed lugs on 10 each end of the tie, each set being adapted to engage respectively one flange of each rail,

channels extending respectively obliquely to the line formed by each set of fixed lugs, and a member in each channel having lugs for engaging the opposite flanges respectively of said rails, and a face extending flush with the tie face and extending closer in a horizontal direction to said line of lugs than the width of the rail.

In testimony whereof, I hereunto affix my 20 signature.

JNO. O. KLEIN.
